(57) **CLAIM**

The ornamental design for a holder for a portable electronic device, as shown and described.

DESCRIPTION

FIG. 1 is a top, front and right side perspective view of a holder for a portable electronic device showing our new design;

FIG. 2 is a bottom, front and left side perspective view thereof;

FIG. 3 is a bottom, rear and right side perspective view thereof;

FIG. 4 is a top, rear and left side perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a reference perspective view of our new design installed on a portable electronic device.

The dash-dash-dash broken lines illustrate environmental structure and form no part of the claimed design.

The dot-dash-dot broken lines represent a boundary that forms no part of the claimed design.
